COLLAPSIBLE RACK

Ferdinand Kramer, Port Chester, N. Y.

Application August 12, 1941, Serial No. 406,475

4 Claims. (Cl. 211—85)

This invention relates to racks and more particularly to racks of the collapsible type for preferably supporting household utensils, such as plates, glasses and the like, which rack can be folded for the purpose of storing it when not in use.

It is an object of the present invention to provide a rack of the above nature which is simple in construction, inexpensive to manufacture and easy to handle during use and for storing purpose.

It is another object of the present invention to provide a rack of the collapsible type which has supporting legs and frame portions extending between said legs and being connectable to the latter.

A further object of the invention is to provide a rack comprising parts articulated thereon which may be swung into a common plane, when it is desired to put the rack away in storage.

Still another object of the present invention is to provide a rack structure having three legs or standards, two of which being connected together through an intermediate part whereby said two legs are formed in U-fashion, the third standard being substantially L-shaped and linked to said intermediate part.

Still a further object of the present invention is to provide a rack having swingable frame portions or holding means which are adapted to hold articles, such as plates, as well as glasses.

Yet, another object of the present invention is to provide a rack of the above nature made of tubular elements, such as steel tubes, which contribute to a very rigid rack structure which can be easily moved from one place to another.

These and other objects and advantages of the invention will appear from the following disclosure thereof together with the attached drawing which illustrates certain forms of embodiments thereof.

These forms are shown for the purpose of illustrating the invention since the same has been found in practice to give satisfactory and reliable results, although it is to be understood that the various parts of which the invention consists can be variously arranged and organized and that the invention is not limited to the precise arrangement or organization of the parts as herein shown and described.

In the drawing:

Fig. 1 is a side elevational view of a rack made in accordance with the invention.

Fig. 2 is a front elevation view thereof.

Fig. 3 is a top plan view of the embodiment shown in Fig. 1, parts being broken away.

Fig. 4 shows the rack in collapsed condition.

Fig. 5 is a detail view of the holding means of said rack in a modified form.

Referring now particularly to the drawing, there is disclosed in Figs. 1 to 3 a rack structure generally designated by numeral 10, which comprises standards or legs 11, 12, which in turn are connected together by traverse or intermediate part 11a, and further comprises standard or leg 13 which is linked at 14 to said intermediate part 11a and through rod 13a at 14a to a transversely extending rod 15 located between the lower ends of standards or legs 11, 12. Preferably within the limits given by standards or legs 11, 12 and 13 when not in folded condition and spaced from each other, there are provided holding means 16, 17 and 18 in the form of ring members 21 each of which being swingably attached to standards 11, 12 by means of pin or bolt 19. The connection of the holding means 16, 17, 18 with standard 13 may be achieved by pin and hole engaging means 20. To this end, each of the holding means 16, 17, 18 has an extension or lug 22 which carries a downwardly directed pin 23 for engagement with an opening 24 provided in projections 25 fixed to standard or leg 13. It will thus be apparent, that each holding means 16, 17, or 18 may be lifted in the direction of arrow A so as to disengage pin 23 from opening 24 of each lug 22 so that ring 21 may pivot about 19 and be swung substantially into the plane of U-shaped standard arrangement 11, 12, 11a.

As it can be seen from Fig. 2 each ring member 21 has two angle pieces 26, 27. One end of each angle piece is fastened at 28 to ring member 21 and carries a knob 29, preferably made of rubber, for a purpose herein later described, the other end of each angle piece being swivelled on bolt or pin 19. Lug 22 also carries a rubber knob 29a.

As clearly shown in Fig. 1 of the drawing, the rubber knobs 29, 29a serve the purpose to hold a plate 30 or similar household utensil in place on ring member 21 and prevent any slipping of the same from the rack 10.

In Fig. 5, there is shown the ring member in modified form comprising a grooved or similarly shaped plate 31 with glass holder elements 32 attached to said plate, said holder elements being made of wire or similar material for receiving glasses or the like therein. Otherwise function

and purpose of plate 31 are similar to that disclosed with respect to ring member 21.

As it will easily be realized from the above, rack 10 may be carried from place to place by gripping the same at standard part 13b or at link connection 14. It is, of course, understood that the ends 33 of standards 11, 12 and 13 may be made rollable in any known manner.

In Fig. 4, rack 10 is shown in its folded condition, when not in use. In order to bring about this condition, holding means 16, 17, 18 are first uncoupled by disengaging pin 23 of each holding means from respective opening 24 of each lug 22 and then swung about pivot or bolt 19 into a position shown in Fig. 4, and finally standard 13 with its parts 13a, 13b may be swung about link connections 14a, 14.

While there has been shown and described and pointed out the fundamental novel features of the invention as applied to the above embodiments, it will be understood that various omissions and substitutions and changes in the form and details of the rack or like device illustrated and its operation may be made by those skilled in the art without departing from the spirit of the invention.

Having thus described the invention what is claimed as new and desired to be secured by Letters Patent is:

1. A collapsible rack comprising inverted U-shaped frame means, a standard including a substantially horizontal upper portion pivotally connected to the inverted U-shaped frame means to swing about a vertical axis, and holding means for articles, said holding means being pivotally connected at one end to said U-shaped frame means to swing about a horizontal axis and detachably engaging at another end thereof with said standard, whereby said holding means and said standard may be simultaneously fixed in operative position.

2. A collapsible rack comprising at least three

members adapted for spaced arrangement, an element connecting two members together forming inverted U-shaped frame means, the remaining member being provided with a horizontal upper portion pivotally connected to said element to swing about a vertical axis, and holding means for supporting articles extending substantially within the space provided between said members, said holding means being pivotally connected to said two members, respectively and detachably engaging with said remaining member.

3. A rack of the character described comprising a frame work including three legs, one of said legs being provided with upper and lower substantially horizontal extensions, a member connecting the upper ends of the other two legs and a further member connecting the other two legs adjacent their lower ends, holding means for supporting articles positioned within said frame work, said extensions being each pivotally connected to said members and adapted to swing about a vertical axis, each holding means being pivotally connected to the other two legs and adapted to swing about a horizontal axis, and coupling means adapted to removably engage said holding means with said one leg.

4. A rack of the character described comprising a substantially inverted U-shaped frame including a transverse member and two legs, a substantially vertical element including two substantially horizontal extensions and one leg, said extensions being pivotally connected to said U-shaped frame and said transverse member, respectively, whereby said vertical element may swing about a vertical axis, and means horizontally pivoted to said U-shaped frame and engageable with said element to hold said means in position at said element and to lock said element in position with respect to said U-shaped frame, said means being adapted to support articles.

FERDINAND KRAMER.
